(57) **CLAIM**

The ornamental design for a double wall vacuum insulated bottle, as shown and described.

DESCRIPTION

FIG. 1 is a perspective view of a double wall vacuum insulated bottle showing our new design; FIG. 2 is a front elevation view of FIG. 1; FIG. 3 is a rear elevation view of FIG. 1; FIG. 4 is a left side elevation view of FIG. 1; FIG. 5 is a right side elevation view of FIG. 1; FIG. 6 is a top plan view of FIG. 1; and, FIG. 7 is a bottom plan view of FIG. 1.

The stippling shown in the drawings is indicative of a contrast in materials between the less dense stippling and the denser stippling.

The broken lines in the drawings depict portions of the double wall vacuum insulated bottle that form no part of the claimed design.
